UNITED STATES PATENT OFFICE.

MAX RUBIN, OF NEW YORK, N. Y.

FAN.

SPECIFICATION forming part of Letters Patent No. 317,211, dated May 5, 1885.

Application filed October 30, 1884. (No model.)

To all whom it may concern:

Be it known that I, MAX RUBIN, of the city, county, and State of New York, have invented new and useful Improvements in Fans, of which 5 the following is a full, clear, and exact description.

Reference is to be had to the accompanying drawings, forming part of this specification, in which similar letters of reference indicate corresponding parts in all the figures.

Figure 1 is a front elevation of one of my improved fans shown open, the case and handle being shown in section. Fig. 2 is a front elevation of one of my improved fans shown 15 closed, the case and handle being shown in section. Fig. 3 is a sectional plan view taken through the line *xx*, Fig. 1. Fig. 4 is a sectional plan view taken through the line *yy*, Fig. 2. Fig. 5 is a section of a side edge of 20 the fan enlarged.

This invention relates to that class of fans that are closed by being drawn into a case, and are opened by being withdrawn from the said case, and has for its object to simplify the construction of such fans and promote certainty 25 in their operation.

The invention relates to a fan constructed with a hollow case having longitudinal slots in its sides, and provided with a longitudinally-perforated handle at its inner end and guide-pins at its outer end, a folded fan having its 30 folds fastened together at one end and its side folds sewed together along their central lines, and cords for opening and closing the fan, as 35 will be hereinafter fully described, and then claimed.

A represents the handle of the fan, which has a longitudinal perforation, B, formed through it for the passage of the operating-cords, and has a case, C, formed upon or attached to its outer end. The case C is made hollow, the interior space being made of such a length and size as to receive within it the folded fan. The sides of the case C do not extend quite to the outer end of the said case, and have central longitudinal slots, D, formed in them from their outer ends to or nearly to 45 their inner ends.

E is the fan, which is made of muslin or 50 other suitable material, and is folded in the ordinary manner. The fan E at one end of its folds has wire F wound around it to bind the

said ends of the folds together, as shown in Figs. 1 and 2. One or more of the side folds of the fan E are sewed together along their 55 central line for a little distance from their outer ends, or, preferably, for their entire length, so that the side parts of the said folds will project as flanges upon the opposite sides of the body of the fan, as shown in Fig. 5, to cause 60 the said side parts of the folds to rest against the inner surfaces of the sides of the case C, while the body of the fan passes through the slots D in the said sides. The side folds of the fan E can be strengthened against wear by 65 strips G, of a stronger material, which strips or the ends of the sewed folds project a little beyond the outer edge of the fan E, and to the said projecting ends are attached the ends of two cords, H, the other ends of which are connected, are passed through the perforation B of the handle A, and have a ring, I, a knob, or a tassel attached to them to prevent them from being drawn back into or through the 70 said handle.

To the corners of the outer end of the case C are attached rivets or pins J, which may be loosely riveted, so as to revolve, or may have small revolving rollers or tubular washers placed upon them to lessen the friction and 75 wear in opening and closing the fan. The pins J are placed at a sufficient distance apart to allow the folded fan E to pass between them when being drawn into and out of the case C.

To the inner end of the fan E is attached the 80 end of a cord, K, which is passed through the perforation B of the handle A, and has a ring, L, a knob, or a tassel attached to its outer end. The ring L is attached to the cord K in such a position that the inner end of the fan E cannot be drawn out of the outer end of the case 85 C. The ring I is attached to the cords H in such a position that the projecting outer ends of the sewed folds, or of the strengthening-strips G, cannot be drawn outward to the ends 90 of the slotted sides of the case C when the fan E is drawn into the said case, so that the said ends will always pass along the inner surfaces of the said slotted sides of the case C when the 95 cords H are drawn upon to open the fan. With 100 this construction, when the fan is open, as shown in Fig. 1, and the cord K is drawn upon, the fan E will be drawn into the case C, the sewed side folds passing around the pins

J. When the fan is closed, as shown in Fig. 2, and the cords H are drawn upon, the sewed side folds of the fan E will be drawn around the pins J and along the inner surfaces of the case C, the side parts of the fan E passing through the slots D, as shown in Fig. 1. With this construction the fan can be readily opened and closed, and when opened its side edges will be supported so as to give a firmness to the fan hitherto unmattained in this kind of fans.

Having thus described my invention, what I claim as new, and desire to secure by Letters Patent, is—

15 1. In a fan, the combination, with the hollow case C, having central longitudinal slots, D, in its sides, and provided with a perforated handle, A, and the folded fan E, having its folds fastened together at one end and its side 20 folds sewed together along their central lines, of the guide-pins J and the cords H K, substantially as herein shown and described, whereby the said fan can be readily opened and closed, as set forth.

25 2. In a fan, the folded fan E, made, substan-

tially as herein shown and described, with its folds fastened together at one end and its side folds sewed together along their central lines to adapt the said side folds to serve as flanges to support the side edges of the said fan when in use, as set forth.

3. In a fan, the combination, with the side folds of the fan E, of cords H, connected with the outer ends of the said side folds and passing over the guide-pins J and through the perforated handle A, substantially as herein shown and described, whereby the said fan can be readily opened, as set forth.

4. In a fan, the hollow case C, constructed, substantially as herein shown and described, with central longitudinal slots in its sides, and provided with a longitudinally-perforated handle, A, and with guide-pins J, whereby the said case is adapted to receive the fan and its operating-cords, as set forth.

MAX RUBIN.
